UNITED STATES PATENT OFFICE.

MILAN H. FISHER, OF CHICAGO, ILLINOIS, ASSIGNOR TO H. L. FISHER MFG. CO., INC., OF CHICAGO, ILLINOIS, A CORPORATION OF ILLINOIS.

STEREOTYPER'S CASTING MACHINE.

Application filed November 9, 1922. Serial No. 599,821.

My invention relates to a stereotyper's casting machine and more particularly to a machine having a pair of spaced platens against one of which the matrix is placed, being held thereagainst by suitable gauges which serve to confine the molten metal to the desired space between the platens.

One of the objects of my invention is the provision of a machine of simple and rugged construction, inexpensive to manufacture, and which may be easily handled in making castings.

In its preferred form my invention contemplates a supporting frame having substantially horizontal and vertical portions; and a further object of my invention is the provision of a pair of platens and suitable hinging and locking means therefor so arranged that the platens may be placed either 20 in a substantially horizontal or vertical position by which arrangement the upper platen may be swung to the vertical position and the lower platen to the horizontal position, the matrix and gauges placed as desired on 25 the inner face of the lower platen, then the upper platen lowered onto the gauges and the two platens locked together. When the platens are locked together, the matrix and gauges are firmly held in position and the 30 two platens may then be swung into the vertical position and molten metal poured into the chamber thus provided and the casting made.

A further object of my invention is the provision of means for connecting the platens to the supporting frame so arranged that said platens may be swung about either of two axes, one of said axes preferably extending vertically and the other horizontally. 35 In carrying out this feature of my invention I preferably provide a yoke pivotally connected to the frame so that it may be swung about a vertical axis and to which the platens are pivoted, the pivotal connection between the platens and the yoke member being so arranged that the platens are substantially balanced on the yoke member and, therefore, easily swung from a horizontal to a vertical position or vice versa.

It is a further object of my invention to provide an arrangement whereby the distance between the platens may be conveniently varied to make castings of different thicknesses, for example, type-high or thin- 45 plate, the latter commonly being termed

"skivers", suitable gauges, of course, being provided for the respective castings.

A further object of my invention is the provision of a novel adjustable hinge for connecting the two platens. 60

A further object of my invention is the provision of novel quick-acting means, preferably adjustable, for locking the two platens together.

A further object of my invention is the provision of a metal pot tiltably mounted on the vertical frame portion in combination with means for heating the metal pot so that molten metal may flow directly from the pot into the casting chamber when the 70 platens are swung upwardly into a vertical position.

The invention consists in the novel constructions, arrangements and devices to be hereinafter described and claimed for carrying out the above stated objects and such other objects as will appear from the following description of certain preferred embodiments illustrated in the accompanying drawings, wherein— 80

Fig. 1 is a perspective view of a machine embodying the principles of my invention, the lower platen being in the horizontal position, and the upper platen having been 75 swung back so that the matrix and gauge bars may be properly positioned on the inner face of the lower platen;

Fig. 2 is a perspective view of the machine, showing the platens in the vertical position so that the molten metal may be 85 poured into the casting chamber therebetween;

Fig. 3 is a plan view of the machine, certain portions being broken away, showing the lower platen in the same position as it occupies in Fig. 1, the upper platen, however, having been swung down into operative relationship with the lower platen and locked to it;

Fig. 4 is a sectional view taken on the 100 line 4—4 of Fig. 3, the two platens, however, having been swung in a horizontal plane from the position shown in Fig. 3 through an angle of 90°;

Fig. 5 is a sectional view taken on the 105 line 5—5 of Fig. 4;

Fig. 6 is a side elevational view, certain parts being sectioned, of one of the hinges 110 preferably employed for connecting the platens;

Fig. 7 is a side elevational view of the preferred form of lock for the platens:

Fig. 8 is a sectional view taken on the line 8—8 of Fig. 7; and

Fig. 9 is a view similar to Fig. 5 but showing the platens, and the hinges and locking means therefor in the positions they occupy when relatively thin gauge bars are employed.

Like characters of reference designate like parts in the several views.

Referring now to the accompanying drawings, the supporting frame includes a rectangular framework comprising longitudinally extending members 12 connected by transversely extending members 13 and a transversely extending medially positioned bridge member 14, the frame being mounted on legs 15. Vertically extending frame members 16 are mounted on the respective frame members 12, being secured thereto by bolts 17.

A yoke member 18 is employed for connecting the platens to the frame, said member being provided with a vertically disposed hub 19, see Figs. 2, 4, 5 and 9, in which the upper end of a pivot pin 20 is secured by a pin 21, the lower end of said pin 20 being adapted to project into an aperture 22 provided in the bridging member 14. The lower platen 23 rests between the arms 18^a of the yoke member, being pivotally connected to said arms by fastening members 24. The upper platen 25 is connected along its lower side, having reference to Fig. 1, by a pair of hinges, designated generally by the reference characters 26, the platens being locked at the opposite side by a pair of quick-acting locking devices, designated generally by the reference characters 27.

In Fig. 1 the platens are in what may be termed the "make-up" position, the upper platen 25 being in a substantially vertical position, and the lower platen 23 in a substantially horizontal position. The platens are held in spaced relationship and the molten metal is confined in the casting chamber formed therebetween by gauges of any desired construction. In the embodiment illustrated, the gauges comprise longitudinally extending bars 28 and a transversely extending bar 29. The bars 28 may be moved toward or away from each other so that castings of various widths may be made.

The matrix (not shown) is placed against the upper side of the platen 23, and the gauge bars are placed thereover in the desired position, after which the platen 25 may be swung down against the upper faces of the gauge bars. The platens then occupy the position shown in full lines in Fig. 3, being locked together by the locking devices 27. The platens may then be swung in a horizontal plane about the axis of the pin 20

through an angle of substantially 90° into the position shown in dotted lines in Fig. 3 and in full lines in Fig. 4. They may then be swung on the members 24 carried by the arms of the yoke through an angle of substantially 90° into the position shown in full lines in Fig. 2 and in dotted lines in Fig. 4, the lower portion of the back side of the platen 23 resting against the adjacent side of the bridge 14. It will be noted that the platens are hinged along one side rather than along one end which considerably shortens the lift of the platen 25. It will also be noted that the pivot members 24 enter the platen 23 substantially medially of its length, thus counter-balancingly mounting the platens on the yoke member. The platens are substantially made and heavily ribbed to prevent warping and are, therefore, quite heavy. Because of the manner in which they are mounted on the supporting frame, however, they may very easily be swung from the position shown in full lines, Fig. 3, into the position shown in full lines in Fig. 4. Since the platens are practically balanced on the yoke, it will be obvious that they may easily be swung from the position shown in full lines in Fig. 4 into the position shown in Fig. 2. The machine is easy and convenient to handle, the only part that need be lifted being the platen 25 when "making-ready" or removing the casting. The machine is very compact and occupies only a small amount of floor space, in fact, much less floor space than any other known machine making castings of the same size.

The two platens may be hinged in any desired manner, but I prefer to use a pair of adjustable hinges of the construction shown in the drawings, particularly in Fig. 6. The respective platens 23 and 25 are provided with lugs 30 and 31. Each lug 30 is provided with an elongated slot 32 for the insertion of a bolt 33. Each lug 31 is perforated for the insertion of a bolt 34. A link 35 is positioned against each side of the lugs 30 and 31, the bolts 33 and 34 passing through apertures provided in the respective ends of said links. Said links, adjacent their lower ends, are provided with apertures 35^a and 35^b, the bolt 33 being shown as extending through the apertures 35^a of the respective links, the purpose of which will presently appear. The lower ends of the respective links preferably are left square so that the links may oscillate only to a limited extent on the bolt 33. The upper ends of the links are rounded so that the platen 25 may be swung on the bolts 34 as pivots. The lug 30 on its upper side is tapped for the insertion of an adjusting screw 36, the inner end of which is adapted to bear against the upper side of the bolt 33, the purpose of which will also presently appear.

The two platens may be locked in co-operating relationship by any desired means, but I prefer to use a pair of quick-acting, adjustable locking devices of the construction shown in the drawings, see particularly Figs. 7 and 8. The respective platens 23 and 25 are provided with lugs 37 and 38. Each lug 37 is provided with a slot 39 for the insertion of a bolt 40. Links 41 adapted to be positioned against the respective sides of the lugs 37 and 38 are pivotally connected at their lower ends to the lug 37 by the bolt 40. Adjacent their upper ends said respective links are provided with perforations 41^a and 41^b, through which a bolt 42 may be inserted, said bolt being shown as extending through the perforations 41^a. A cam member 43 is attached to the upper ends of said links by the bolt 42 and is adapted to engage the seat formed on the upper surface of the lug 38, said cam member having a handle portion 43^a. When the platens are in the position shown in Fig. 1, the locking devices hang downwardly, out of the way, and, when the platens are in the position shown in Fig. 3, the locking devices may be swung upwardly to bring the cam members into engagement with the seats on the respective lugs 38, thus locking the platens together, as shown in Figs. 2 to 5, inclusive. The lugs 37 are tapped for the insertion of adjusting screws 44, the inner ends of said screws being adapted to bear against the upper sides of the respective bolts 40.

In Figs. 1 to 8, inclusive, type-high gauges are shown in place between the two platens, and, when such gauges are used, the bolts 33 of the hinges 26 are inserted through the apertures 35^a of the links 35, and likewise the bolts 42 of the locking devices 27 are inserted through the apertures 41^a of the links 41. In Fig. 9 thin-plate gauges 45 are shown in position between the two platens, and, in that case, the bolts 33 of the hinges 26 are inserted through the apertures 35^b of the links 35, and the bolts 42 of the locking devices 27 are inserted through the apertures 41^b of the links 41, thereby bringing the platens together in closer relationship. It will be seen, therefore, that adjustable connections are provided between the links 35 of the respective hinges 26 and the platen 23 and also adjustable connections are provided between the links 41 and the cam members 43 of the respective locking devices. In order to take care of any inaccuracies in manufacture and any wear that may develop, provision is made for varying the distances between the bolts 33 and 34 of the respective hinges and the bolts 40 and 42 of the respective locking devices, this being accomplished by turning the screws 36 of the hinges and the screws 44 of the locking devices. By this arrangement a very fine adjustment is obtained and the

platens may be brought into close fitting engagement against the respective sides of the gauge bars.

A metal pot 46 is positioned on brackets 47 carried by the respective vertical frame members 16. At each side the metal pot is provided with a pair of spaced, laterally projecting lugs 46^a which are adapted to lie in suitable recesses provided in the bracket members 47. This arrangement makes it impossible to tilt the metal pot accidentally and yet permits the molten metal to flow from the pot through the spout 46^b thereof directly into the casting chamber formed between the two platens. The platen 23 is provided with a portion 23^a to direct the molten metal into the casting chamber. The portion 23^a may be made in the form of a handle, see Fig. 3, to facilitate handling the platens. The pot and metal therein are preferably heated by suitable burners 48 connected with a source of gas or gasoline.

The frame is provided with a foot-piece 49, see Figs. 2, 5 and 9, which forms a support for the right-hand end of the platens, having reference to Figs. 1 and 3, when they are in the positions shown therein. The piece 49 and the bottom of the yoke 18 prevent the platens rocking to any appreciable extent on the members 24, the piece 49 being particularly useful when a small casting is made in the bottom of the casting chamber, in which case the tendency for the platens to tilt clockwise being much greater than when full size castings are made.

I do not intend to limit my invention to the details of construction shown and described herein, except only in so far as certain of the appended claims are specifically so limited, as it will be obvious that various modifications may be made by those skilled in the art without departing from the principles of the invention.

I claim:

1. A stereotyping casting machine comprising a supporting frame, a pair of platens, and means connecting said platens to said frame and adapted to permit said platens to be swung about either of two axes, said axes extending substantially at right angles to each other.

2. A stereotyping casting machine comprising a supporting frame, a pair of platens, and means connecting said platens to said frame and adapted to permit said platens to be swung about either a vertical axis or a horizontal axis.

3. A stereotyping casting machine, comprising a supporting frame, a pair of platens pivotally connected together at one side, and means pivotally connecting one of said platens at an intermediate point with said frame on a horizontal axis extending transversely of the platens whereby the platens may be swung into horizontal position with

one platen superposed on the other or into vertical position with their ends uppermost.

4. In a stereotyper's casting machine, the combination of a supporting frame, a pair of platens pivotally connected together at one side, and pivotal connections between one of said platens and said frame, comprising a member pivotally connected with one of said platens on a horizontal axis extending transversely of the platens whereby the platens may be swung into horizontal position with one superposed on the other, and means pivotally connecting said member with said frame on a vertical axis whereby the superposed platens may be swung horizontally on said frame.

5. In a stereotyper's casting machine, the combination of a supporting frame, a pair of platens pivotally connected together at one side, and pivotal connections between one of said platens and said frame, comprising a member pivotally connected with one of said platens on a horizontal axis extending transversely of the platens whereby the platens may be swung into horizontal position with one superposed on the other, means pivotally connecting said member with said frame on a vertical axis whereby the superposed platens may be swung horizontally on said frame, and means for limiting the swing of the platens about the horizontal axis when swung horizontally on the frame into their "making ready" position.

6. A stereotyper's casting machine comprising a supporting frame, a yoke pivotally connected to said frame, a pair of platens, and means to lock said platens together, said platens being pivotally connected to said yoke, the axes of said pivotal connections extending substantially at right angles to each other.

7. A stereotyper's casting machine comprising a supporting frame, a yoke pivotally mounted on a vertical axis on said frame, a pair of platens, means to lock said platens together, and means for pivotally mounting one of said platens on a horizontal axis on said yoke.

8. A stereotyper's casting machine, comprising a supporting frame, a yoke pivotally mounted on a vertical axis on said frame, a pair of platens, means for locking said platens together, and means for pivotally mounting one of said platens on said yoke on a horizontal axis located substantially midway between the ends of said platens whereby the two platens when locked together are substantially balanced on said yoke.

9. A stereotyper's casting machine, comprising a supporting frame, a yoke pivotally mounted on a vertical axis on said frame, a pair of relatively long platens pivotally connected together at one side on an axis extending longitudinally thereof, means for

locking said platens together, and means for pivotally mounting said platens on said yoke in substantially centered position with respect to the vertical axis of the yoke on a horizontal axis located substantially midway between the ends of the platens for holding said platens when locked together in substantially balanced condition on said yoke.

10. A stereotyper's casting machine, comprising a supporting frame, a yoke pivotally mounted on a vertical axis on said frame, two platens pivotally connected together at one side thereof, means for pivotally mounting one of said platens on a horizontal axis on said yoke in substantially counterbalanced position thereon, and positively acting means serving to limit movement of the platens about the horizontal axis when they are swung about the vertical axis into their "making ready" position.

11. A stereotyper's casting machine comprising a supporting frame, a yoke pivotally connected to said frame so it may swing about a vertical axis, a pair of platens, means to lock said platens together, said platens being pivotally connected to said yoke so that they may be swung from a horizontal position to a vertical position, or vice versa, and a metal pot pivotally mounted on said frame and so arrange that molten metal may flow therefrom into the casting chamber when said platens are in the vertical position.

12. A stereotyper's casting machine comprising a supporting frame, a yoke pivotally connected to said frame so it may swing about a vertical axis, a pair of platens, means to lock said platens together, said platens being pivotally connected to said yoke so that they may be swung from a horizontal position to a vertical position, or vice versa, a metal pot pivotally mounted on said frame and so arranged that molten metal may flow therefrom into the casting chamber when said platens are in the vertical position, and means for heating said pot.

13. In a stereotyper's casting machine the combination of a pair of platens, a hinge for said platens at one side comprising a link pivotally connected at one end to one of said platens and at the other end to the other of said platens, one of said connections being adjustable, and a lock for said platens at the opposite side comprising a cam member associated with one of said platens, and a link pivotally connected at one end to the other of said platens and at the other end to said cam member, one of said last mentioned connections being adjustable.

14. In a stereotyper's casting machine, the combination of a pair of platens, and a hinge for said platens comprising a link, a fastening member pivotally connecting said link at one end to one of said platens, a fastening member pivotally connecting said link

- at the other end to the other of said platens, and adjustable means co-operating with one of said members and adapted to vary the distance between said members.
- 5 15. In a stereotyper's casting machine, the combination of a pair of platens, and a hinge for said platens comprising a link, a fastening member pivotally connecting said link at one end to one of said platens, a fastening member pivotally connecting said link at the other end to the other of said platens, one of said connections being adjustable, and adjustable means co-operating with one of said members and adapted to vary the distance between said members.
- 10 16. In a stereotyper's casting machine, the combination of a pair of platens, and a lock for said platens comprising a cam member associated with one of said platens, a link, a fastening member pivotally connecting said link at one end to the other of said platens, a fastening member pivotally connecting said link at the other end to said cam member, and adjustable means co-operating with one of said fastening members and adapted to vary the distance between said fastening members.
- 15 17. In a stereotyper's casting machine, the combination of a pair of platens, and a lock for said platens comprising a cam member associated with one of said platens, a link,
- a fastening member pivotally connecting said link at one end to the other of said platens, a fastening member pivotally connecting said link at the other end to said cam member, one of said connections being adjustable, and adjustable means co-operating with one of said fastening members and adapted to vary the distance between said fastening members.
- 20 18. A stereotyper's casting machine comprising a supporting frame, a yoke pivotally connected to said frame and adapted to be swung about a vertical axis, a pair of platens pivotally carried by said yoke and adapted to be swung about a horizontal axis, and means to prevent rocking of said platens about the horizontal axis when they are in the "making ready" or "casting-removing" positions.
- 25 19. A stereotyper's casting machine comprising a supporting frame, a yoke pivotally connected to said frame and adapted to be swung about a vertical axis, a pair of platens pivotally carried by said yoke and adapted to be swung about a horizontal axis, and a supporting member carried by said frame and adapted to prevent rocking of said platens about the horizontal axis when they are in the "making ready" or casting-removing" positions.

MILAN H. FISHER.
